UNITED STATES PATENT OFFICE

MELVILLE A. DELAWARE, OF WEST SCARBORO, MAINE

AMUSEMENT DEVICE

Application filed July 6, 1931. Serial No. 549,000.

This invention relates to new and useful improvements in amusement devices, and more particularly it pertains to a device of this character which is more in the nature 5 of a toy for children.

It is one of the objects of the present invention to provide an amusement device which will give to a child, the sensation of travelling in an airplane or similar device.

10 It is a further object of the invention to provide a device of the aforementioned character which will be spaced from the ground and which will be of such a character that the occupant of the car will be prefer- 15 ably out of reach of the ground.

A still further object of the invention resides in a novel form of mechanism whereby the car or device may be propelled through the air while occupied by a passenger.

20 A still further object of the invention resides in the provision of a propeller in imitation of a full size propeller which is rotated as the car is moved through the air.

With the above and other objects in view, 25 reference will be had to the accompanying drawings wherein;

Figure 1 is a perspective view of a device constructed in accordance with the present invention and showing its manner of use,

30 Figure 2 is an enlarged detail side elevational view of a portion of the device,

Figure 3 is a view in front elevation of the device portions thereof being shown in section, the view being taken on the line 3—3 of Figure 2,

35 Figure 4 is a plan view of the car with portions thereof being shown in section, the view being taken on the line 4—4 of Figure 2, and;

40 Figure 5 is a view in rear elevation partly in section, the view being taken on the line 5—5 of Figure 2.

Referring again to the drawings, the device includes a suspension cable 10 upon 45 which the car 11 is mounted for movement in either direction. For mounting the car 11 for movement along the suspension cable 10, two upright members 12 and 13 are em- 50 ployed. These members are connected at their lower ends to the car 11 and as best

illustrated in Figure 3, their upper ends are formed with a hook or the like 15. Mounted in the hook portion of the upper end of each of these members, there is a grooved pulley 16 mounted upon a pintle or the like 17 in 55 order that it may rotate freely in the hooked portion. Carried by the pintle 17 of the forward member, there is a grooved pulley 18 the purpose of which will be hereinafter more specifically mentioned.

In the present illustration of the invention, the suspension cable 10 is mounted upon posts or the like 19 although other means may be employed for supporting this suspension cable 10 without departing from the spirit of 60 the invention.

It will be apparent that the grooved rollers 16 of the members 12 and 13 are engaged over the suspension cable 10, and thus form means by which the car may be moved along 70 the suspension cable 10 in a manner to be hereinafter described.

Means is provided for propelling the car 11 along the suspension cable 10, and in the present illustration of the invention this 75 means consists of two cables 21 and 22 which extend parallel to the suspension cable 10 but are preferably in a lower plane. The cables 21 and 22 are carried by the ends of cross arms 23 which in turn are carried by the posts 19 heretofore mentioned and thus these cables 21 and 22 are spaced from each other as illustrated.

To propel the car along the suspension cable 10, the occupant of the car grabs the cables 21 and 22 and by exerting a slight pull thereon can move the car in either direction along the cable 10 the same moving freely upon the roller 16 in the manner heretofore 85 described.

Means is also provided to prevent lateral swinging motion of the car or accidental dis- 95 placement of the roller 16 from the cable 10, and in the present illustration of the invention this means consists of a cross arm 26 carried by the forward vertical member 12. This cross arm as best illustrated in Figure 3 is provided with eyes or the like 30 which receive the cables 21 and 22 and thus prevent 100

lateral movement of the car, and provides stability therefor.

In the present embodiment of the invention, the car is in imitation of an airplane or the like, and consists of a main body portion 31 having a seat 32 and a transversely extending member 33 in imitation of the plane of an airplane. Mounted at the front portion of the body 31, there is a bumper 34 formed from a strip of metal bent upon itself and secured to the body as at 35 by bolts or the like and mounted within this bumper, there is a member 36 in imitation of an airplane propeller. This propeller is rotatably mounted and has attached thereto a pulley 37 over which a belt 38 passes. The belt is in the form of a cord or rope, and also passes over the pulley 18 heretofore mentioned in such a manner that as the car is moved in the manner heretofore described, the belt or cord 38 will serve to rotate the propeller.

A foot rest is provided and this may consist of angular members 40 which are secured as at 41 to the sides of the car and depend therefrom and may be adjustably secured by means of a pin, screw or the like engageable in openings 43 in the body of the car.

From the foregoing it will be apparent that the present invention provides a new and improved amusement device particularly adapted for use by children, and which is safe, and at the same time highly efficient for the purpose intended.

While the invention has been herein illustrated in a preferred form, it is to be understood that the invention is not limited to the specific construction herein shown, but that it may be carried out in other forms without departing from the spirit thereof.

Having thus described the invention, what is claimed as new and what it is desired to secure by Letters-Patent of the United States, is:

1. A device of the character described comprising a suspension cable, a car suspended from said cable and movable therealong, a pair of spaced cables extending parallel to said suspension cable and adapted to be grasped by an occupant of the car to propel the car along said suspension cable, means carried by the car and engaging said second mentioned cables to prevent lateral swinging movement of the suspended car.

2. A device of the character described comprising a suspension cable, a car suspended therefrom and movable therealong in either a forward or rearward direction, and means for guiding said car in its movement in either direction, said last mentioned means comprising a pair of spaced cables, and a guide arm carried by the car and having sliding engagement with said spaced cables.

3. A device of the character described comprising in combination, a suspension cable,

a car in imitation of a flying machine suspended from said cable, and movable therealong, a bumper carried by one end of the car, a propeller mounted within said bumper, and means operated by movement of the car along the suspension cable for rotating said propeller.

4. A device of the character described comprising in combination, a suspension cable, a car in imitation of a flying machine suspended from said cable, and movable therealong, a bumper carried by one end of the car, a propeller mounted within said bumper, and means operated by movement of the car along the suspension cable for rotating said propeller, said last mentioned means including a plurality of pulleys and a driving belt passing therearound.

In testimony whereof I affix my signature.
